(57) **CLAIM**

The ornamental design for a grinder pump assembly, as
shown and described.

DESCRIPTION

This application incorporates by reference concurrently filed
U.S. patent application Ser. No. 11/748,231, entitled "Wire-
less Liquid Level Sensing Assemblies And Grinder Pump
Assemblies Employing The Same" by Capano et al. All the
material from the concurrently filed U.S. patent application
Ser. No. 11/748,231, entitled "Wireless Liquid Level Sensing
Assemblies And Grinder Pump Assemblies Employing The
Same" by Capano et al. which is essential to the claimed
design is included in this application. It is understood that any
material in the concurrently filed U.S. patent application Ser.
No. 11/748,231, entitled "Wireless Liquid Level Sensing
Assemblies And Grinder Pump Assemblies Employing The
Same" by Capano et al. which is not present in this application
forms no part of the claimed design.

FIG. 1 is a perspective view of a grinder pump assembly in
accordance with the new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom view; and,

FIG. 7 is a perspective view of the grinder pump assembly of
FIG. 1 shown in an alternative configuration of use.

The broken lines in the figures are for illustration purposes
only and form no part of the claimed invention.
